VARIABLE PITCH PROPELLER CONTROL

John Hays Hammond, Jr., Gloucester, Mass.

Application April 17, 1941, Serial No. 388,944

3 Claims. (Cl. 170—163)

This invention relates to variable pitch propellers and more specifically to means for automatically varying the pitch of a propeller in accordance with changes in the speed of the vessel so as to maintain the most efficient propulsion conditions with a fixed power output under varying conditions of wind and weather.

The invention further relates to means for automatically recording the pitch of the propeller blades, the speed of the vessel, and the speed of the propeller slip-stream.

The invention also provides means for varying the rate of change of pitch of the propeller blades in accordance with the amount of change of speed of the vessel.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Figure 1 illustrates diagrammatically the automatic recording system as applied to a marine vessel, and

Figure 2 illustrates diagrammatically the system as applied to the control of the pitch of the propeller blades in accordance with the speed of the vessel.

Like reference characters denote like parts in the several figures of the drawings.

In the following description and in the claims parts will be identified by specific names for convenience, but they are intended to be as generic in their application to similar parts as the art will permit.

Referring to the accompanying drawings and more particularly to Figure 1, the hull of a marine vessel is indicated at 11. The vessel is driven by means of a propeller 12, which is provided with adjustable blades 13 and which has an outboard bearing in a rudder post 14. The propeller 12 is attached to the end of a hollow shaft 15 which passes thru a bearing 16. A rudder 17 is mounted on the rudder post 14. The shaft 15 is driven by a prime mover 20 which may be of any desired type and is preferably provided with a governor, not shown, for maintaining a constant speed of rotation.

The blades 13 are connected to a variable pitch

mechanism 18 which may be of any well known and standard construction such as that manufactured by the Escher-Wyss Company of Zurich, Switzerland, the details of which form no part of the present invention and are accordingly not specifically set forth herein. This mechanism, in general, comprises a rod 19 slidable longitudinally within the shaft 15 and connected to control the pitch of the blades 13. The rod 19 is actuated by a piston 21 in a fluid pressure cylinder 27a. Fluid for actuating the piston 21 is supplied by a pump 26 through a control valve 25 and a distribution valve 25a which communicates with the cylinder 27a through ducts, not shown, in the shaft 15.

A motor 21 rotates a worm 22 which operates to move the upper end of a floating lever 23, which, in turn, is pivoted to the end of a valve rod 24 which controls the valve 25. The piston 21 is connected by a rod 28 to a collar 29 which is slidably mounted on the shaft 15 and engages the lower end of the lever 23 so that the position of this end of the lever corresponds to the pitch of the blades 13.

Stops 32 are provided for limiting the maximum and minimum pitch of the blades 13. The fluid pump 26 is driven either by a motor 33 or a belt 35 from the shaft 15. A reservoir 36 and a supply tank 37 are provided for the necessary fluid. The motor 21 is provided with two windings for causing it to rotate in opposite directions. These windings are connected to the two poles of a double throw switch 38, the blade of which is connected thru a battery 39 to the common return to the motor 21.

It is to be understood that other pitch control devices may be employed in place of that referred to above, for varying the pitch of the propeller blades 13 in response to actuation of the motor 21. A particular type is shown for purposes of illustration only.

A recording mechanism 40 is provided which contains a moving strip of paper 41 which is caused to move upward at a uniform rate by any well known means and upon which three records 42, 43 and 44 are made by three styluses 45, 46 and 47 which are mounted on the ends of the pointers of three indicators 48, 49 and 50.

The indicator 48 is of the mechanical type and is connected by a wire 51 to the upper end of the lever 23 and indicates the pitch at which the blades 13 are set. The indicators 49 and 50 are of the electrical type and are electrically connected to two generators 52 and 53 which are driven by two propellers 55 and 56, the former

being located in the slip-stream of the propeller 12 and the latter being located below the hull 11. These devices for measuring the velocity of the water are of well known and standard construction and need not be more fully described herein and operate in such a way as to cause the pointers of the indicators 49 and 50 to move an amount proportional to the velocity of the water in which the propellers 55 and 56 are located.

Operation

In the operation of the recording system shown in Figure 1 the vessel is taken out for trial trips under various conditions of wind and weather and the power delivered by the prime mover 20 is kept substantially constant by means of the governor. Some of the runs are made against the wind, some are made across wind when its effect is negligible and others are made with the wind.

In each run after the vessel is on its course and conditions have become stabilized the pitch of the blades 13 is varied by operating the switch 23 until the maximum speed under the given conditions has been obtained as indicated by the pointer of the indicator 50. The setting of the blades 13 is accomplished by moving the blade of the switch 38 into the upper or lower position which will cause the motor 21 to move the upper end of the lever 23 to the left or right to increase or decrease the pitch in a well known manner, the angle of pitch being indicated by the pointer of the indicator 48.

After a set of runs under various conditions of wind and weather has been made a series of curves 42, 43 and 44 are obtained giving the maximum speed obtainable under each particular condition of wind and weather with constant power output and also the optimum blade angle under each set of conditions. The data from these curves will be used in the construction of a cam to be described in connection with Figure 2.

In Figure 2 is shown the mechanism for controlling the pitch of the blades 13 in accordance with the speed of the vessel under various conditions of wind and weather and with constant power output. The mechanism shown in this figure is similar to that shown in Figure 1 up to and including the battery 39, the corresponding parts being given the same numbers. In this figure, however, the recorder 40 has been replaced by a pitch control mechanism 60 and the generator 52 and propeller 55 have been eliminated.

The pitch control mechanism 60 comprises a base 61 upon which are mounted the indicator 48, which is connected to the lever 23 by the wire 51 and the indicator 50, which is connected to the generator 53 and the propeller 56. Rotatably mounted over the indicator 48 is a segmental member 62. Mounted on but insulated from this member are six contact segments 63-68 which cooperate with a contact 70 attached to the end of the pointer of the indicator 48. The contact 70 is connected to one side of the battery 39.

The segments 63 and 68 are connected to two conductors 71 and 72 which are connected to the reversing windings of the motor 21. The segments 64 and 65 are connected to two resistors 73 and 74 the other ends of which are connected to the conductor 71. The segments 66 and 67 are connected to two resistors 75 and 76 the other ends of which are connected to the conductor 72.

Rotatably mounted above the indicator 50 is a member 78 which is provided with the segment of a worm wheel 79. Meshing with the worm wheel segment 79 is a worm 80 which is secured to the shaft of a motor 81 which is mounted on the base 61. Attached to the pointer of the indicator 50 is a contact 82 which cooperates with two contact segments 83 and 84 which are mounted on but insulated from the member 78.

- 10 The contact segments 83 and 84 are connected to the reversing windings of the motor 81. The common return of the motor 81 is connected to one side of a battery 85, the other side of which is connected to the contact 82.
- 15 The member 78 is connected by a link 86 to a cam 87 which is pivotally mounted at 88 to the base 61. The face of the cam 87 is engaged by a roller 90 mounted on an arm 91 which is pivotally mounted at 92 to the base 61. A spring 93 tends to hold the roller 90 in engagement with the face of the cam 87. A link 95 connects the arm 91 to the lower end of the segmental member 62.

Operation

- 25 In the operation of the form of the invention shown in Figure 2 the pitch of the blades 13 is set at the normal operating angle for the speed, at which it is desired to operate the vessel. The setting of the blades 13 is accomplished by moving the blade of the switch 38 into the upper or lower position which will cause the motor 21 to move the upper end of the lever 23 to the left or right to increase or decrease the pitch in a well known manner, the angle of pitch being indicated by the pointer of the indicator 48.

The vessel is then brought up to the desired speed at which time the generator 53 will produce a certain voltage, due to the rotation of the propeller 56, which will be transmitted to the indicator 50, the contact 82 of which will take up a position corresponding to the speed of the vessel. As the contact 82 rotates it will engage one or the other of the segments 83 or 84 causing an electrical circuit to be closed from the battery 85 thru the motor 81 which will cause this motor to be rotated in such a direction that the insulation between the contact segments 83 and 84 will follow the motion of the contact 82.

This motion is transmitted by the link 86 to the cam 87 which will thus take up a position corresponding to the speed of the vessel. As the cam 87 is rotated it will cause a rotation of the arm 91 which by means of the link 95 will cause the segmental member 62 to be rotated an amount

55 determined by the speed of the vessel and the shape of the cam 87. As the member 62 rotates it will cause either contact segment 65 or 66 to engage the contact 70 causing an electrical circuit to be closed from the battery 39 thru either resistor 74 or resistor 75 and the motor 21, which will cause this motor to be slowly rotated in such a direction that the lever 23 will, acting thru the wire 51 and indicator 48, cause the contact 70 to follow the motion of the insulation between the contacts 65 and 66.

The motion of the lever 23 will operate the valve 25 which will allow fluid under pressure to pass from the pump 26 to the cylinder 27a by means of the ducts in the shaft 15. This will actuate the piston 27 which, by means of the rod 19 and the link mechanism, will cause the propeller blades 13 to slowly change their pitch. In this way the pitch of the blades 13 is caused to 75 follow the motion of the member 62, which, as

previously stated, is determined by the speed of the vessel and the shape of the cam 87.

If the speed of the vessel should change more rapidly so that either segment 64 or 67 engage the contact 70 then either resistor 73 or 76 will be thrown in the circuit with the motor 21. As resistors 73 and 76 have less resistance than resistors 74 and 75 the motor 21 will be caused to rotate faster, thus changing the propeller pitch more rapidly to take care of the more rapidly changing conditions. If the conditions change so quickly that either segment 63 or 68 engages contact 70 then no resistance will be thrown in the circuit of the motor 21 and it will rotate at its maximum speed, thus changing the propeller pitch at a maximum rate. The stops 32 are provided so that the propeller pitch is prevented from exceeding certain limits beyond which it could not operate efficiently under any conditions.

In this way the pitch of the propeller blades 13 is varied in accordance with the speed of the vessel and the shape of the cam 87. The shape of this cam is determined from the graphs on the paper strip 41 (Figure 1). As already stated these curves show the most efficient propeller blade angle, curve 42, to give the maximum ship speed, curve 44, with constant power output under various conditions of wind and weather. Thus for each possible ship's speed taken from curve 44 the corresponding propeller blade angle is obtained from curve 41 and the radius of the cam 87 for each point is thereby determined. It is thus seen that in this way the propeller blades 13 are always set at the optimum angle for the conditions under which the ship is operating at that time.

The recording mechanism shown in Figure 1 may also be used for determining the optimum relation between the ship's speed and the propeller slip-stream speed which would be necessary 40 in constructing the cam shown in my co-pending application Serial No. 388,943. This relationship is obtained from the curves 44 and 43.

Although only a few of the various forms in which this invention may be embodied have been 45 shown herein, it is to be understood that the invention is not limited to any specific construction

but might be embodied in various forms without departing from the spirit of the invention or the scope of the appended claims.

What is claimed is:

1. In a system for driving a vessel, a variable pitch propeller having blades, speed indicating means directly responsive to the speed of the vessel, pitch control means to control the pitch of said blades, and a follow-up system interconnecting said speed indicating means and said pitch control means, said follow-up system including a non-linear response element designed in accordance with pre-calculated characteristics selected in accordance with the optimum pitch angle for various vessel speeds and arranged to control the pitch of said blades in accordance with said pre-calculated characteristics.
2. In a system for driving a vessel, a variable pitch propeller having blades, speed indicating means directly responsive to the speed of the vessel, pitch control means to control the pitch of said blades and a follow-up mechanism actuated by said speed indicating means, a cam member actuated by said follow-up mechanism and having pre-selected characteristics suited to obtain the desired operating relationship between the vessel's speed and the propeller pitch, a second follow-up mechanism actuated by said cam member, and means controlled by said second follow-up mechanism to actuate said pitch control means, whereby the pitch of said blades is varied as a function of the speed of the vessel which is dependent upon the shape of said cam.
3. In a vessel, a variable pitch propeller having blades, driving means for said vessel, means to vary the pitch of said blades, indicating means actuated by said last means to indicate the blade pitch, means responsive to the speed of travel of said vessel, indicating means actuated by said last means, means responsive to the speed of the propeller slip stream of said vessel, indicating means actuated by said last means, all of said indicating means comprising styluses and a common chart cooperating with said styluses to produce a record of the relationship between propeller pitch, ship speed and slip stream speed.

JOHN HAYS HAMMOND, JR.
